UNITED STATES PATENT OFFICE.

OLE F. APLIN, OF CULBERTSON, MONTANA.

GRAIN-BIN FEED.

Application filed February 26, 1927. Serial No. 171,319.

This invention relates to a grain bin feed meant particularly to be applied to a grain elevator of the usual type. Its object is to provide a device to regulate the feed of grain 5 from the dumping pit of the elevator into the "leg" or upright casing, in which the bucket conveyor operates to taken the grain to a high point on the elevator. It is my purpose to provide a device that is positive and can 10 be applied without alteration of the ordinary hand equipment, and to which other doors or slides can be added later and which will be useful on either side of the elevator; which is adaptable to the usual arrangements 15 of slides found on elevators and which will not be affected by the settling of floors and timbers.

Referring to the drawings,

Figure 1 is a side elevation of the conveying means partly in section, showing the device applied to the leg of a grain elevator.

Fig. 2 shows the leg of the grain elevator in front elevation with the feed device applied thereto.

Fig. 3 shows the rear elevation of the elevator leg showing two doors or slides thereof controlled by the feed mechanism.

Fig. 4 shows a detail of one of the spacing triangles which separate the control levers 20 of the device.

Referring now particularly to Fig. 1 numeral 1 indicating the leg of the grain elevator, 2 indicates the conveyor with the buckets 3, 4 is the inclined floor of the dumping pit. 5—5 indicate the feed doors of the elevator leg controlled by a system of levers, of which 6—6 are the ones immediately operating the doors shown. The levers 6 are raised and lowered by a crank shaft 7—7 which is hinged 40 on the end of the beam 8. The middle crank of this crank shaft is attached to the lever 6 and the other end is attached to a strut 9. The struts 9 are provided with a series of holes near their outer ends, permitting adjustable fastening of the crank thereto. In this way, the distance of opening of the doors 5—5 is regulated which produces a corresponding change in the rate of admission of grain.

The strut members 9 are rotatably connected at their opposite ends, with the end of lever 10, which is fulcrumed on the triangular quadrant support 11. The quadrant 12 is

provided with notches into which the pawl fits thereby serving to hold the lever in place in the well known manner.

55

Referring now to Figs. 2 and 3, 5 indicates the admission door with the lever 6 fastened thereto. In this view, the operation of the lever 6 by crank shaft 7 is apparent. Fig. 3 illustrates this construction applied to an 60 elevator leg to control two doors instead of one. Fig. 3 constitutes a rear view of Fig. 2.

Referring to Figs. 1 and 2, 14 constitutes a spring return means for the doors or slides 65 after they have been opened. One end is attached to the door as shown at 13, while the other end is fast to the floor as at 16.

It is to be understood that the invention is not limited to three lever systems for operating three doors or slides, as shown, but may 70 consist of an unlimited number.

I will now describe the operation of the device, which is as follows:—

The lever 10 is pulled to the right, shifting the struts 9 longitudinally which in turn 75 rock the crank shafts to lift these levers 6 and the doors or slides 5 upward an amount governed by the limit of movement of the crank shafts. In returning the door to shut position the spring 14 is of assistance in making a quick cut-off. The return is accomplished by moving the lever 10 to a position in the middle of the quadrant.

I claim:—

1. In combination a pair of parallel grain 85 elevator legs each of which having a vertically movable slide, crank shafts journaled adjacent each leg, each of which have operative connection with one of the slides, a manually adjustable lever, and longitudinally shiftable 90 levers connected with the manually adjustable lever and having operative connection with the crank shafts whereby to actuate the slides upon movement of the manually actuated lever.

2. In combination a grain elevator leg having a vertically movable slide, a crank shaft journaled to one side of the slide and having operative connection with the latter, a hand lever arranged adjacent the leg and 100 a lever having pivotal connection with the hand lever and provided with a plurality of longitudinally aligned openings, any one of which being engageable with the crank shaft

whereby to vary its limit of movement to correspondingly limit the movement of the slide.

3. In a device of the character described, one or more slide doors of an elevator leg, a link attached thereto, a compound crank, one arm of which is attached to the link, a support for the crank, a strut adjustably fas-

tened to the other arm of the crank and a lever pivoted to the other end of the said strut, said lever being pivoted on a quadrant and having a means attached thereto for locking the lever on the quadrant. 10

OLE F. APLIN.
